Primary Examiner — Lauren R Calve(74) *Attorney, Agent, or Firm* — Gottlieb, Rackman & Reisman, PC(57) **CLAIM**

The ornamental design for a clear hanger, as shown and described.

DESCRIPTION

FIG. 1 is a perspective view of a clear hanger showing my new design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof; and,

FIG. 7 is a bottom plan view thereof.

The broken lines shown in the drawings are included for the purpose of illustrating portions of the clear hanger that form no part of the claimed design.

1 Claim, 5 Drawing Sheets(56)
